LASTING MACHINE

Joseph Fossa, Salem, Mass., assignor to United
Shoe Machinery Corporation, Flemington, N. J.,
a corporation of New Jersey

Application October 19, 1945, Serial No. 623,289

7 Claims. (Cl. 12—9)

1

This invention relates to machines for use in the manufacture of shoes and particularly to a novel and improved apparatus for progressively lasting with an adhesive. While herein illustrated as embodied in a lasting machine of the type disclosed in United States Letters Patent No. 2,411,827, issued in my name on November 26, 1946, it is to be understood that the invention is of broader utility and not limited to use in a machine organization of the exact character exemplified in the mentioned patent.

As now performed on existing types of lasting machines, the operation of progressively lasting with an adhesive involves the preliminary step of coating the inside face of the lasting margin of the stock and/or the marginal portion of the bottom face of the shoe-bottom part with adhesive of a type which when permitted to dry for a predetermined period will become tacky, i. e., capable of bonding the lasting margin securely to the shoe-bottom part in lasted position, and which will remain in this tacky condition for an appreciable period and at least long enough for the lasting operation to be performed. Such drying period not only consumes valuable time and thus slows up production but also it frequently happens, due to carelessness or some unavoidable delay, that the adhesive is permitted to dry for too long a time and thus reaches a non-tacky condition, with the result that it must be reactivated and again dried for the proper time to render it tacky before the lasting operation can proceed, thus involving still further delay and expense.

Moreover, the use of thermoplastic adhesives, for progressive lasting in accordance with the procedure outlined above, is impractical, inasmuch as these adhesives, after application in a heated liquid or semi-liquid state, would cool so quickly as to reach a non-tacky condition before the lasting operation could be performed.

Accordingly, it is an object of this invention to provide an improved machine for lasting progressively with an adhesive which is capable of satisfactory operation with adhesive which is in a non-tacky condition, thus avoiding delay and obviating the need for the exercise of care to see that the lasting operation is performed exactly at the time when the adhesive has reached a tacky condition, as well as making it possible to use types of adhesive which could not hitherto be employed for progressive lasting. With this object in view, the herein illustrated machine, which has means for working the lasting margin of the stock to be lasted into lasted position over a shoe-bottom part, in different locations progressively along

2

the edge of the shoe bottom, including means for pressing the lasting margin, in each of said locations, against the shoe bottom, to secure it in lasted position, is provided with means for applying heat to the lasting margin of the stock and/or the shoe-bottom part to activate and render tacky adhesive thereon before the lasting margin is pressed against the shoe-bottom part. While, in the herein illustrated machine, the lasting instrumentalities comprise gripper jaws which seize the stock and tension it by drawing it inwardly from the edge of the shoe bottom and over a portion of a shoe-bottom-engaging member, and the means for pressing the stock against the shoe-bottom part is in the form of a presser member that moves first toward the shoe bottom and thereafter moves in a direction to feed the shoe, it is to be understood that the use of other types of progressively acting lasting devices are within the scope of the invention.

In accordance with this invention, the means for applying heat may take various forms and two desirable arrangements are illustrated herein. In one, which is particularly well adapted for application to a lasting machine of the type herein illustrated, means are provided for heating a shoe-bottom-engaging member over which the lasting margin of the stock is drawn by gripper jaws, while in the other the machine is provided with means for directing a blast of hot, gaseous medium, such as hot air, directly against the adhesive on the lasting margin and/or shoe-bottom part. With each arrangement, however, the effect is the same and heat is applied during the lasting operation to activate and render tacky the adhesive, whether it be on the lasting margin, shoe-bottom part, or on both, before the lasting margin is pressed against the shoe-bottom part. Furthermore, the lasting margin of the stock will be rendered pliable and more readily workable by the application of heat thereto with the result that the lasting operation will be facilitated and improved results obtained.

The above and other objects and features of the invention will be apparent from the following detailed description of the embodiments thereof illustrated in the accompanying drawings and will be pointed out in the claims.

In the drawings,

Fig. 1 is a view in side elevation of a portion of a lasting machine embodying features of this invention;

Fig. 2 is a view in front elevation of the operating elements of the machine shown in Fig. 1;

Fig. 3 is a view similar to Fig. 1 but showing a modification; and

Fig. 4 is a view in front elevation of the operating elements of the machine shown in Fig. 3.

Referring to the drawings, the lasting machine therein illustrated is, except as modified for the purposes of this invention and in the manner set forth below, the same as the machine disclosed in the above-mentioned patent and is provided with a gripper comprising a rear jaw 10 and a front jaw 12, a shoe-bottom-engaging member 14, a presser-feed-foot 16, a feed-retaining finger 18, and an edge-gage roll 20. These parts are supported on and operated by mechanism contained within a hollow head 24. The rear gripper jaw 10 is carried by a block 30 in which a rod 32 is slidably mounted, and secured to the outer end of this rod is the front gripper jaw 12 which is urged toward the rear gripper jaw 10 by a tension spring 34.

The shoe-bottom-engaging member 14 is in the form of an arm 40 which extends downwardly from a hub journaled on a shaft 42 mounted in an overhanging portion of the head 24, and as in the machine of my prior patent, means operated by a foot treadle, not shown, are provided for moving the shoe-bottom-engaging member to the operating position, in which it appears, from an inoperative position, to which it is swung, to the left and in a clockwise direction, Figs. 1 and 3, by a spring, not shown. Also extending from this same hub is an arm 44 to which is connected a link 46 that operates means for holding the gripper jaws 10 and 12 open when the shoe-bottom rest is in its inoperative position, in the manner explained in detail in my prior application. The presser-feed-foot 16 and feed-retaining finger 18 are mounted on the outer ends of lever arms 50 and 52, respectively, that extend into the head 24 where they are connected to operating mechanism contained therein.

As is explained in my prior patent referred to above, the illustrated machine operates to last stock, such for example as the lasting margin M of the upper U, shown on a last L on which there is assembled an insole I, in the following manner. The shoe is presented to the machine while the shoe-bottom rest is in its inoperative position and with the gripper jaws held open. Then, as the treadle of the machine is depressed, the shoe-bottom-engaging member 14 moves into its operative position where it engages the marginal portion of the insole I. The gripper jaws first close on the upper and then move to the left to pull the upper inwardly from the edge of the shoe bottom and over the shoe-bottom-engaging member 14, thereby to tension the stock heightwise of the last and draw its lasting margin in over the shoe bottom. When the gripper has completed this tensioning action and just as the jaws are about to open to release the stock, the presser-feed-foot 16 descends to the position shown in Fig. 2 and presses the tensioned and overdrawn margin M firmly against the insole. Immediately thereafter, the presser-feed-foot moves in a direction to feed the shoe, to the left in Fig. 2, while the feed-retaining finger 18 moves upwardly and out of engagement with the overlasted margin of the upper to permit such feeding movement. At the completion of this feeding movement the presser-feed-foot 16 is elevated and returned to its original position during the time that the gripper jaws are again operated to tension the next adjacent portion of the upper, the feed-retaining finger 18 now descending to

apply additional pressure to the overlasted margin and to prevent retrograde movement of the shoe. If the inside face of the lasting margin M and/or the marginal edge of the insole I, is coated with adhesive in a tacky condition, the pressure applied by the presser-feed-foot and feed-retaining finger will cause the upper to be bonded securely in lasted position on the insole, as will be readily understood. However, should the adhesive be in a non-tacky condition, as may frequently be the case, a satisfactory bond will not be obtained and the upper will not be held securely in lasted position.

To avoid such difficulty, and to make it possible to last progressively where the adhesive is not in a tacky condition, the illustrated machine is provided with means for applying heat to the adhesive on the lasting margin and/or shoe-bottom part to activate and render the adhesive tacky, during the lasting operation and before the lasting margin is pressed against the shoe-bottom part by the presser-feed foot 16.

In the form of my invention illustrated in Figs. 1 and 2, this is accomplished by heating the shoe-bottom-engaging member. Referring to these figures, the shoe-bottom-engaging member 14 has a projecting portion 60 provided with a flat bottom surface 62 for engaging the marginal portion of the insole I and an inclined face 64 against which the lasting margin M is drawn during the operation of the gripper to tension the upper. Formed integrally with the arm 40 is an extension 66 provided with a bore 68 in which is positioned an electrical heating unit 70. Leads 72 and 74 extend from this unit to a suitable source of electrical energy, not shown, so that the projecting portion 60 of the shoe-bottom-engaging member will be heated to a temperature sufficient to activate adhesive on the lasting margin M and/or on the marginal portion of the insole I, and render such adhesive tacky, by virtue of direct engagement thereof with the surfaces 62 and/or 64, during the operation of the machine and before the lasting margin is pressed against the shoe-bottom part by the presser-feed-foot 16. The degree of heating of the shoe-bottom-engaging member may be varied to suit different operating conditions and suitable automatic controls may, if desired, be utilized to regulate the temperature.

Heat may also be applied by directing a blast of a hot gaseous medium, such for example as hot air, onto the inside face of the lasting margin of the stock, and/or against the marginal portion of the shoe-bottom member, and Figs. 3 and 4 show a machine provided with means for accomplishing this purpose.

Referring to these figures, the machine therein shown, which is the same as that illustrated in Figs. 1 and 2, has supported on its head portion 24 a tube 100 in which is mounted a resistance coil 102 from which leads 104 and 106 extend to a source of electrical energy, not shown. Connected to one end of this tube, by means of an elbow 108, is a pipe 110 that extends to a suitable source of air under pressure, not shown, while an outlet nozzle 112 is connected to the opposite end of this tube by means of an elbow 114. A valve of appropriate construction 116 is arranged in the pipe 110 and this valve has an operating arm 118 which is connected to the arm 40 which carries the shoe-bottom-engaging member 14, by means of a link 120. In the positions of the parts as shown in Fig. 3, this valve is open so that air under pressure will pass through the coil

102 and, after being heated thereby will be discharged through the nozzle 112. When the treadle is released and the shoe-bottom member swung to its inoperative position, however, the valve 116 will be closed and the discharge of heated air through the nozzle 112 will be cut off.

As will be apparent with the above arrangement, hot air will be discharged through the nozzle 112 at all times during the operation of the machine in the lasting of a shoe, and this stream of hot air will be directed onto the inside face of the lasting margin M and also against the marginal portion of the insole I so as to activate and render tacky adhesive on these parts.

With each of the arrangements above described, heat is applied to the lasting margin and/or the shoe-bottom part, during the lasting operation, and adhesive on either or both of these parts will be activated and rendered tacky before the lasting margin is pressed against the shoe-bottom part. Thus a secure bonding of the lasting margin to the shoe-bottom part is assured even though the adhesive may have been in a non-tacky condition at the beginning of the lasting operation. Moreover, such application of heat to the upper stock will tend to render it pliable and more readily workable so that the lasting operation itself is greatly facilitated.

In using lasting machines provided, in accordance with the features of this invention, with means for applying heat to the lasting margin of the stock to be lasted, and/or the marginal portion of the shoe-bottom part, no care need be exercised to make certain that the lasting operation is performed at exactly the time when previously applied adhesive has reached the proper tacky condition. Also it is possible to use adhesives which could not hitherto have been employed for progressive lasting with machines of known types. For example, the lasting margin and/or the shoe-bottom part may be coated with thermoplastic adhesive which is allowed to cool before the parts are assembled on the last, or at least before the lasting operation is initiated, and such coating, or coatings, will be activated by the application of heat thereto during the lasting operation. In fact, even when lasting stock coated with adhesive, such for example as solvent-type cements or latex, which adhesive coatings may be more or less tacky, the application of heat thereto will greatly hasten the setting of such cements and thus improve the bond between the lasting margin and the shoe part.

Having thus described the invention, what I claim as new and desire to secure by Letters Patent of the United States is:

1. In a lasting machine, the combination with a member for engaging the bottom of a shoe adjacent to the edge thereof, means for tensioning stock to be lasted, in different locations progressively along the edge of the shoe bottom, by drawing the lasted margin of the stock in each location inwardly over the shoe-bottom-engaging member and in a direction substantially parallel to the bottom of the shoe, and means operating in time relation to said tensioning means for pressing the overdrawn lasting margin in each location against the bottom of the shoe, of means for applying heat to the lasting margin and shoe-bottom part, during the operation of said tensioning and overdrawing means, to activate adhesive thereon before the lasting margin is pressed against the shoe-bottom part by said pressing means.

2. In a lasting machine, the combination with

a member for engaging the bottom of a shoe adjacent to the edge thereof, means for tensioning stock to be lasted, in different locations progressively along the edge of the shoe bottom, by drawing the lasting margin of the stock in each location inwardly over the shoe-bottom-engaging member and in a direction substantially parallel to the bottom of the shoe, and means operating in time relation to said tensioning means for pressing the overdrawn lasting margin in each location against the bottom of the shoe, of means positioned adjacent to said shoe-bottom-engaging member for directing a blast of hot, gaseous medium against the lasting margin and shoe-bottom part, during the operation of said tensioning and overdrawing means, to activate adhesive thereon before the lasting margin is pressed against the shoe-bottom part by said pressing means.

3. In a lasting machine, the combination with means for working the lasting margin of stock into lasted position over a shoe-bottom part, progressively in different locations along the edge of the shoe bottom, including means for pressing the overlasted margin in each location against the shoe-bottom part, of a member constructed and arranged to contact the bottom of the shoe and the lasting margin of the stock, during the operation of said overworking means, and means for heating said member to activate adhesive on the lasting margin and shoe-bottom part before the lasting margin is pressed against the shoe-bottom part by said pressing means.

4. In a lasting machine, the combination with means for working the lasting margin into lasted position over a shoe-bottom part, progressively in different locations along the edge of the shoe bottom, including means for pressing the overlasted margin, in each location against the shoe-bottom part, of a member constructed and arranged to contact the lasting margin of the stock during the operation of said overworking means, and means for heating said member to activate adhesive on the lasting margin, before the lasting margin is pressed against the shoe-bottom part by said pressing means.

5. In a lasting machine, the combination with means for working the lasting margin into lasted position over a shoe-bottom part, progressively in different locations along the edge of the shoe bottom, including means for pressing the overlasted margin, in each location against the shoe-bottom part, of a member constructed and arranged to contact the bottom of the shoe, during the operation of said overworking means, and means for heating said member to activate adhesive on the shoe-bottom part, before the lasting margin is pressed against the shoe-bottom part by said pressing means.

6. In a lasting machine, the combination with means for tensioning the stock, in different locations progressively along the edge of a shoe-bottom part, and for drawing the lasting margin of the stock in each location inwardly over the shoe-bottom part, and means for pressing the lasting margin in each location against the shoe-bottom part, of a member constructed and arranged to contact the shoe-bottom part and the lasting margin of the stock, during the operation of said tensioning and overdrawing means, and means for heating said member to activate adhesive on the lasting margin and shoe-bottom part before the lasting margin is pressed against the shoe-bottom part by said pressing means.

7. In a lasting machine, the combination with

a member for engaging the bottom of a shoe adjacent to the edge thereof, means for tensioning stock to be lasted, in different locations progressively along the edge of the shoe bottom, by drawing the lasting margin of the stock in each location inwardly over the shoe-bottom-engaging member and in a direction substantially parallel to the bottom of the shoe, and means operating in time relation to said tensioning means for pressing the overdrawn lasting margin in each 10 location against the bottom of the shoe, of means for heating said shoe-bottom-engaging member to activate adhesive on the lasting margin and shoe-bottom part, during the operation of said

tensioning and overdrawing means, before the lasting margin is pressed against the shoe-bottom part by said pressing means.
